UNITED STATES PATENT OFFICE

2,595,280

BLADE DISPENSING MAGAZINE

Charles L. Metzler, Palisades Park, N. J., assignor
to Gillette Safety Razor Company, Boston,
Mass., a corporation of Delaware

Application December 30, 1947, Serial No. 794,639

5 Claims. (Cl. 206—16)

1

This invention comprises a new and improved device for containing and dispensing sharp-edged blades such as safety razor blades.

For many years it has been the practice to package and dispense safety razor blades in individual envelopes or wrappers. The removal of a blade so dispensed from its envelope is likely to impair the extremely thin and fragile shaving edge of the blade by accidental contact with the paper of the wrapper. Unwrapping the blade also necessitates some delay in preparing for shaving, with objectionable liability of cutting the fingers of the user.

The object of the present invention is to provide an improved device for dispensing unwrapped blades which may be constructed at a minimum of expense and so economically employed for packaging and dispensing relatively small unit quantities of blades, for example four or five blades, at a time. At the same time it is important that the package should maintain the blades fully protected with their cutting edges out of contact with the walls of the dispenser, and that in the ejecting operation the individual blades should be accurately guided so as to obviate the danger of chance contact.

With these ends in view, my invention comprises in one aspect a device formed from a single piece of sheet metal bent to form a bottom, upstanding side walls and inturned resilient cover flanges which are separated by a longitudinal slot that is enlarged in a limited area sufficient to provide access to the uppermost blade of the stack within the container and which provides space for aligned studs projecting from the bottom of the dispenser and serving to locate the blades while in the dispensing device and also to guide them as they emerge therefrom.

These and other features of the invention will be best understood and appreciated from the following description of a preferred embodiment thereof selected for purposes of illustration and shown in the accompanying drawings in which:

Fig. 1 is a view in perspective of the metal blank from which the dispensing device is made;

Fig. 2 is a view in perspective of the complete device; and

Fig. 3 is a view of the device in longitudinal section on the line 3—3 of Fig. 2.

The dispensing device of my invention may be constructed from a single integral blank of spring sheet metal or molded from other resilient sheet material. As shown in Fig. 1, the flat blank may be die cut from sheet material and longitudinally

2

scored to define a substantially rectangular bottom portion 10 having slightly curved end edges which merge into narrow longitudinal zones or areas 11 and 12 on one side. The outer zone 12 in turn merges into a longitudinally disposed flap 13 having end edges which are oppositely curved with respect to those of portion 10 and a symmetrically located recess 14 in its edge.

At its other side, the bottom portion 10 merges into similar narrow longitudinal zones or areas 15 and 16. The outer zone 16 in turn merges into a longitudinally disposed flap 17 corresponding to the flap 13 and having a symmetrically arranged recess 18 on its outer edge.

15 The enveloping portion of the dispenser is completely formed from the blank shown in Fig. 1. The scored lines define the zones 11—16, determining the fold lines or bending lines. In forming the enveloping portion of the dispenser the zones or areas 11 and 15 are first bent upwardly to form an angle of approximately 45 degrees with the bottom portion 10. The zones or areas 12 or 16 are then bent inwardly at an angle of approximately 90 degrees with the previously bent areas 11 and 15, and thus form the side walls of the dispenser. Each of these has in effect a longitudinal corrugation which imparts stiffness to the dispenser as a whole.

10 The enveloping portion of the dispenser is now completed by bending the flaps 13 and 17 inwardly at such an angle that they tend to rest normally upon the bottom 10 or upon a blade or a stack of blades located upon the bottom. Thus the angle between the previously bent zone 12 and the inturned flap which now forms a cover flange is somewhat greater than 90 degrees and in practice the inturned flanges 13 and 17 may partake of a concave curvature due to the initial tension imparted to them and which exists between their inner edges and their line of bending.

45 The dispenser is completed by the addition of a pair of aligned studs 19 and 20 having upwardly and outwardly diverging top edges and being located in the space or slot between the opposite edges of the inturned flanges 13 and 17. These studs may be formed separately and welded in place or they may be formed by being struck upwardly from the material of the bottom portion 50 10. The manner in which they are provided is of secondary importance so long as they perform the functions of positioning the blades within the dispenser and accurately guiding them as they are removed or ejected.

55 The dispenser is herein shown as containing

a stack of five blades of a well-known commercial type, that is to say, double-edged safety razor blades 21 each having a longitudinal median slot and reduced unsharpened end portions. These blades are arranged in the dispenser in longitudinally staggered relation, that is, three blades 21 are impaled upon the stud 20 while two blades 21' are impaled upon the stud 19. Accordingly the blades 21, and this includes the blade uppermost in the stack as shown in Fig. 2, are free to move only toward the left as indicated by the arrows borne by each blade, while the blades 21' are free to move only toward the right. Movement of any blade in the wrong direction is positively prevented by engagement of its solid end with the shoulder formed by the outer vertical wall of one of the studs 19 or 20.

The recesses 14 and 18 of the flaps 13 and 17 are oppositely disposed and become in the finished dispenser an open area affording access by the user to the topmost blade of the stack. The concave curvature of the inturned flanges fits the contour of the thumb or finger of the user and guides it comfortably into contact with the surface of the blade and thus permits him to eject one blade at a time in the direction shown by the arrows on the blade, turning the dispenser end for end between each projecting operation.

As herein shown, the blades of the stack are yieldingly held down by engagement of the inturned flanges 13 and 17 of the magazine. However, the flanges are sufficiently flexible to yield upwardly when the solid rear end of a blade rides up the inclined face of either of the studs 19 or 20 in being removed from the magazine.

Having thus disclosed my invention and described in detail an illustrative embodiment thereof, I claim as new and desire to secure by Letters Patent:

1. A blade-dispensing device comprising a sheet metal envelope having a substantially rectangular bottom, upstanding side walls each having a longitudinal corrugation therein, and inturned cover flanges of spring material having opposed edges which tend to flex always toward said bottom and are separated by a narrow longitudinal space, and aligned blade-locating ribs spaced from each other and projecting upwardly from the bottom to points above the inner edges of said flanges.

2. A blade-dispensing device comprising a sheet metal envelope having a flat elongated bottom portion, upstanding side walls merging into inturned cover flanges of spring material which slope in concave curvature toward the bottom

portion, being spaced and having oppositely disposed recesses providing a finger opening through which the user may reach blades within the envelope, and studs having oppositely disposed edges sloping upwardly and outwardly in the space between the edges of said flanges to a level above the cover flanges.

3. A blade-containing and dispensing device comprising an integral piece of sheet metal bent to form a bottom, upstanding side walls and inturned resilient cover flanges separated from end to end by a longitudinal slot which is symmetrically enlarged throughout its center portion, and spaced aligned studs projecting from the bottom through the slot between the flanges and having oppositely inclined edge faces which extend above the level of the cover flanges.

4. A blade-dispensing device comprising an integral envelope of spring sheet metal including a substantially rectangular bottom, upstanding side walls, and resilient inturned flanges tending at all times to spring toward the bottom of the envelope and being spaced apart at their opposite edges thereby defining a longitudinal slot between them, and blade-locating projections disposed in the slot thus provided and having inclined upper edges which traverse the inner edges of the said flanges.

5. A blade dispensing device for longitudinally slotted razor blades, comprising walls forming an elongated enclosure having a pair of inturned cover flanges separated by an open space, a flat-sided stud having an abruptly shouldered outer edge and an inclined inner edge rising above the cover flanges, and a stack of longitudinally slotted blades empaled upon said stud, the said flanges being resilient and normally holding down the stack but being adapted to flex upwardly temporarily as the solid end of a slotted blade is moved forcibly up the inclined inner edge of the said stud.
